UNITED STATES PATENT OFFICE.

EMIL GRUENEELDT, OF CLEVELAND, OHIO, ASSIGNOR, BY MESNE ASSIGNMENTS, TO
THE BAKER R & L COMPANY, OF CLEVELAND, OHIO, A CORPORATION OF OHIO.

MEANS FOR PREVENTING OVERHEATING ELECTRIC RESISTANCES.

1,188,647.

Specification of Letters Patent. Patented June 27, 1916.

Application filed January 6, 1913. Serial No. 740,401.

To all whom it may concern:

Be it known that I, EMIL GRUENEELDT, a subject of the Emperor of Germany, residing at Cleveland, in the county of Cuyahoga and State of Ohio, have invented certain new and useful Improvements in and Relating to Means for Preventing Overheating Electric Resistances, of which the following is a specification.

10 This invention relates to means for protecting an electric circuit against overheating in the circuit, more particularly where a resistance is introduced in the circuit.

For the purpose of illustrating my invention I have herein selected to disclose one embodiment of it in providing against overheating of a resistance ordinarily employed at certain times in the circuit between a storage battery and an electric motor in a motor vehicle. Careless or thoughtless operators of the motor vehicle have been known to apply the brakes with the circuit closed through a resistance. Under such circumstances the resistance has been known to become so highly heated by the current flowing through it as to set fire to the motor vehicle.

Figure 1 is a side elevation of a resistance with my invention applied thereto. Fig. 2 is a plan view of the same. Fig. 3 is an end elevation. Fig. 4 is a perspective view of a grid. Fig. 5 is a perspective view of an insulating tube detached. Fig. 6 is a perspective view of a binding post detached. Fig. 7

35 is a diagram of the resistant circuit. In the drawings, 1 represents a series of metal resistance sections or grids. They may be of any suitable construction. They are shown arranged side by side in a series. 40 For illustration I have selected cast metal grids of the conformation shown in Fig. 4. They are assembled on tubular sections 2 of suitable insulating material, such as mica.

The grids or sections may be spaced apart 45 in any desired manner. Each is shown as having three enlarged portions, 1', 1^a, 1^b, each enlarged portion having an opening through it to receive one of the insulating tubes or cores 2. Between the adjoining enlarged portions of adjacent grids may be placed metal washers 3 and, where the grids are to be insulated each from the next adjacent one or ones, suitable insulating disks or washers 4 may be used, such as mica 50 disks.

5 are binding posts or connectors for receiving electrical conductors or wires which convey current to and from the resistance. Those illustrated in the drawings are formed by bending a piece of metal upon itself, as shown in Fig. 6, so as to comprise a tubular portion 4' and flat portions 4^a. The latter are drilled at 4^b to receive the insulating tubes 2.

6 are screws for binding the conductors in the posts 5.

7 are binding posts similar in construction to the binding posts 5, the purpose of these, however, being to properly support in the electrical circuit fuses which have relatively low melting points. Each of the binding posts 7 carries an inwardly turned tube 8 of metal, preferably a good conductor of electricity. The inner ends of two aligned tubes 8 are spaced apart to receive fuses 9. The fuses 9 have ends 9' arranged to be inserted in two aligned tubes 8 and U-shaped extensions 9^a disposed between adjacent resistance grids or sections.

The resistance sections, washers both metal and insulating, and the tubes or cores 2 may be held together in any suitable manner. For this purpose I have shown a framework consisting of strips of metal 11, forming a rectangle. One of these rectangles is arranged at each side of the resistance and together with the parts of the resistance they are held or bound together by bolts 12 which extend through the insulating tubes 2. For the purpose of supporting the resistance I have shown sections of metal 12' likewise held in place by the bolts 12.

Each of the fuses 9 has a current carrying capacity in excess of any current which is to be passed through it. Each of the fuses also is formed of material which besides being a conductor of electricity, has a relatively low thermal melting point, so that should the circuit be closed through the resistance, although the current flowing through the fuse 100 be below the carrying capacity of the fuse but sufficient to heat up the resistance, then, when the heat generated in the resistance reaches a certain point or degree of temperature, such heat will cause the fuse to melt 105 and open the circuit. The fuses are so disposed and arranged as to serve to preclude the heat generated in the resistance from exceeding the predetermined point at which the fuse melts and opens the circuit.

Fig. 7 is a diagram illustrating the circuit in the resistance shown. Assuming that the current enters at the binding post R^1 , it flows through the first grid then 5 through the fuse 9 which may be, for example a 75 ampere fuse, then through the second grid to the third grid and thence fourth grid to the binding post R^3 . If the circuit is closed between the binding post R^1 and 10 R^3 , only one fuse, which we have assumed to be a 75 ampere fuse is in the circuit. In the event that heat generated in the grids due to the flow of current there-through exceeds a predetermined tempera- 15 ture, that is, the temperature at which the fuse 9 will melt, the fuse will burn out.

The next fuse in the circuit may be for a larger capacity in amperes than the first fuse, say 100 amperes, when it alone is in 20 the circuit its capacity will be sufficient to permit a hundred amperes to flow, nevertheless should the heat of the resistance grids between which this fuse is located exceed a predetermined degree, the fuse will burn 25 out or melt and open the circuit because of the existence of such degree of heat.

I have used this invention extensively in electric motor vehicles in connection with a resistance employed between the storage 30 battery and an electric motor and have

found it entirely suitable for preventing the overheating of the resistance so as to set fire to the motor vehicle.

To those skilled in the art of making apparatus of the class described, many alterations in construction and widely differing embodiments and applications of my invention will suggest themselves, without departing from the spirit and scope thereof. My disclosures and the description herein 40 are purely illustrative, and are not intended to be in any sense limiting.

What I claim is:—

A resistance for an electric circuit and a fuse connected in electric circuit with said resistance, said fuse having a U-shaped section with its base disposed between sections of said resistance and constituted to be melted at a predetermined temperature due to heat generated in said resistance by current flowing therethrough lower in value than the electrical carrying capacity of the fuse.

In testimony whereof I affix my signature, in the presence of two witnesses.

EMIL GRUENFELDT.
